To all whom it may concern:

Be it known that I, Edwin F. Guth, a citizen of the United States and a resident of Webster Groves, St. Louis County, Missouri, have invented a new, original, and ornamental Design for Electric Illuminating Fixture, of which the following is a specification, reference being had to the accompanying drawing, forming part thereof, which is a perspective view of an electric il-

I claim:

The ornamental design for an electric illuminating fixture, substantially as shown and described.

EDWIN F. GUTH.
